DESIGN FOR A FUR BEATER

Ludwig F. Cramer, Minneapolis, Minn., and
Victor R. Lawson, Wollaston, Mass.; said
Lawson assignor to Maurice H. Glassman, Inc.,
Boston, Mass., a corporation of Massachusetts

Application November 30, 1938, Serial No. 81,476

Term of patent 3½ years

To all whom it may concern:

Be it known that we, Ludwig F. Cramer and Victor R. Lawson, both citizens of the United States and residing, respectively, in the city of Minneapolis, Hennepin County, State of Minnesota, and city of Wollaston, Norfolk County, State of Massachusetts, have invented a new, original, and ornamental Design for a Fur Beater, of which the following is a specification, reference being had to the accompanying drawing, forming a part thereof, wherein,

Fig. 1 is a perspective view illustrating a fur beater showing our new design;

Fig. 2 is a side elevation of the same fur beater, and

Fig. 3 is a view in rear elevation of the same fur beater.

We claim:

The ornamental design for a fur beater, substantially as shown.

LUDWIG F. CRAMER.
VICTOR R. LAWSON.
